Primary Examiner — Sandra Snapp*Assistant Examiner* — Katherine Glennon(74) *Attorney, Agent, or Firm* — Egbert Law Offices, PLLC(57) **CLAIM**

The ornamental design for a sprinkler timer, as shown and described.

DESCRIPTION

FIG. 1 is a perspective view of a sprinkler timer showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The features presented in broken lines are for illustrating environmental structure only and form no part of the claimed design.
